CLAIM

The ornamental design for a barbed wire holder, or similar article, as shown and described.

DESCRIPTION

FIG. 1 is a front elevational view of a barbed wire holder, or similar article, showing my new design.

FIG. 2 is a right side elevational view of the barbed wire holder, or similar article, the left side elevational view being a mirror image thereof.

FIG. 3 is a rear elevational view thereof.

FIG. 4 is a top plan view thereof.

FIG. 5 is a bottom plan view thereof.

FIG. 1.

FIG. 2.

FIG. 3.

FIG. 4.

FIG. 5.
